UNITED STATES PATENT OFFICE.

ARTHUR M. WIGHT, OF NEW YORK, N. Y.

COLLAPSIBLE BOX.

1,043,379.

Specification of Letters Patent.

Patented Nov. 5, 1912.

Application filed September 14, 1911. Serial No. 649,252.

To all whom it may concern:

Be it known that I, ARTHUR M. WIGHT, citizen of the United States, residing at New York, in the county of New York and State of New York, have invented a certain new and useful Improvement in Collapsible Boxes, of which the following is a full, clear, concise, and exact description.

My invention relates to boxes or crates, and more particularly to collapsible boxes or crates such as are used for shipping purposes. Its object is to provide a box which is cheap to manufacture, and in which the sides, bottom, ends and top do not require to be nailed or otherwise secured together by hinges or the like.

A further object is to provide a box which, in its knockdown condition can be packed in very compact form, taking up approximately no more space than the lumber itself of which the box is constructed.

The several features of my invention may be more readily understood by reference to the accompanying drawings, in which—

Figure 1 is a perspective view of a box, showing the preferred embodiment of my invention; Fig. 2 is a perspective view of the box in its collapsed or knockdown condition, showing the compact shape it then takes; Fig. 3 is a section on the line 3—3 of Fig. 1; Fig. 4 is a section on the line 4—4 of Fig. 3; Figs. 5 and 6 are sections on the lines 5—5 and 6—6, respectively, of Fig. 2; and Fig. 7 is a fragmentary detail in section showing a modified form of interlocking cleats.

Like reference characters refer to like parts throughout the several views.

The frame of each of the box-ends E, E may consist of vertical stiles 3, 3 to the outer faces of which are secured, near the top and bottom of the stiles, the transverse cleats 2 and 4 of one box-end and the transverse cleats 2 and 5 of the other box-end.

The box-bottom B is provided at each of its ends with upturned, inwardly extending end-retaining members, that is with members which extend over and interlock with the box-ends. Said end-retaining members are preferably in the form of transverse cleats 1, 1, which are adapted to have a tongue and groove or wedge engagement with transverse cleats 2, 2 secured at the bottom edge of the box ends E, E. The cleats 1 and 2 are preferably of the form shown in Figs. 1 and 3, the cleats 1 provid-

ing overhanging flanges beneath which the cleats 2 engage to prevent upward displacement of said ends. In other words the cleats 1 of the bottom constitute hooks which hook over the lower edges of the box-ends. The box-ends are thus held at their lower edges against outward displacement and have, as it were, inwardly releasing tongue and groove engagement with the box-bottom B. 65

The box-cover C has upon its under surface at its ends the transverse cleats 6, 7. The cleat 6 preferably hooks over the cleat 4 of the box-end and when said cleats are thus drawn into locking engagement the 70 cleat 7, at the opposite end of the box-cover, fits over and upon the outside of the cleat 5. Each of the cleats 5 and 7 upon their adjacent faces is provided with a longitudinal groove, said grooves together constituting a 75 keyway for the longitudinal strip or key 8 which serves to lock the cover C in place. The cover thus serves to hold the ends E, E at their upper edges against outward displacement. The cover and bottom overlap 80 the edges of the sides and prevent their vertical displacement.

The sides S, S of the box fit between the ends E, E and thus hold said ends against inward displacement. Said sides are themselves held against outward displacement by the stiles 3 which they overlap. The stiles 3 preferably project a slight distance above and below the box-sides and thus inclose the cover C and the bottom B, thereby holding said cover and bottom against lateral displacement. 90

If preferred, instead of the cleats 1 and 2 or 4 and 6, cleats 1^a and 2^a, such as are shown in Fig. 7, may be employed, said cleats having the usual well-known tongue and groove fit with each other. It will also be understood that the terms ends and sides are relative terms, and while I have used said terms with their usually accepted meanings, the term end preferably referring to the shorter and the term side to the longer width of the box, my invention is not limited in this respect. It will be noted that my invention provides a box or crate which does not require the use of metal straps or latches. Such straps and latches are difficult, if not impossible, for the ordinary box-maker to construct. The box of my invention, on the contrary, is one which can be made in any box factory equipped with the common equipment of any box-making factory. 100 105 110

I claim:

1. In a collapsible box or crate, a bottom; end-retaining members secured to said bottom at the ends thereof, said members being each provided with an inwardly extending portion overhanging the upper surface of said bottom; ends having transverse bars engaging beneath said overhanging portions, whereby said ends have inwardly releasing locking engagement with said bottom; sides fitting between said ends; and means for locking said ends at their upper edges against outward displacement.
2. In a collapsible box or crate, a bottom; transverse cleats secured to said bottom at the opposite ends thereof providing upon the upper surface of each end of said bottom an inwardly opening transverse groove; ends having at their lower edges transverse cleats provided with outwardly extending tongue portions fitting in said grooves; sides fitting between said ends; and a cover provided with means for locking said ends at their upper edges against outward displacement.
3. In a collapsible box or crate, a bottom; transverse cleats secured upon said bottom at the ends thereof, said cleats each having an inwardly extending overlying flange; ends having a frame provided with vertical stiles and transverse cleats secured near the lower edges of said stiles and engaging beneath said flanges, said stiles extending upon the opposite sides of said bottom below said cleats; sides fitting between said ends; and a cover provided with means for locking said ends at their upper edges against outward displacement.
4. In a collapsible box or crate, a bottom having end-retaining members provided with inwardly extending flanges overlying said bottom, ends having transverse bars engaging beneath the flanges of said end-retaining members, sides fitting between said ends, and a cover provided with means for locking said ends at their upper edges against outward displacement.
5. In a collapsible box or crate, the combination with box-ends having a frame consisting of vertical stiles and transverse cleats secured near the upper and lower edges of said ends, said stiles extending beyond said cleats to provide for the reception of the box-bottom and box-cover between the ends of said stiles; of said box-bottom having at its ends upturned inwardly extending end-retaining members extending over and interlocking with the cleats at the lower edges of said ends; sides fitting upon the inside of said stiles between said ends, said sides resting upon said bottom; and said cover provided with means at each end for interlocking with the cleats at the upper edges of said ends to hold the upper edges of said ends against outward displacement.
6. The combination with a box or crate having an outwardly projecting cleat at the upper edge of each of its ends, of a cover supported at its ends upon said cleats, the ends of said cover projecting beyond said cleats, said cover being provided upon its under surface at one end with a cleat having a tongue and groove engagement with the corresponding cleat upon the end of the box and at its other end with a cleat fitting over the cleat upon the corresponding end of the box, and a removable key for interlocking said last mentioned cleats.

In witness whereof, I, hereunto subscribe my name this 13th day of September, A. D., 1911.

ARTHUR M. WIGHT.
